UNITED STATES PATENT OFFICE.

GEORGE WILLIAM EUKER, OF RICHMOND, VIRGINIA, ASSIGNOR TO EDWIN O. MEYER, OF RICHMOND, VIRGINIA.

ELECTROTHERAPEUTIC APPARATUS.

SPECIFICATION forming part of Letters Patent No. 701,185, dated May 27, 1902.

Application filed February 26, 1902. Serial No. 95,728. (No model.)

To all whom it may concern:

Be it known that I, GEORGE WILLIAM EUKER, a citizen of the United States, residing at Richmond, in the county of Henrico and State of Virginia, have invented certain new and useful Improvements in Electrotherapeutic Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to improvements in electrotherapeutic apparatus, and more especially to the converting and controlling of alternating currents of high pressures, such as usually furnished for commercial use, and rendering the same available for therapeutic and other medical or surgical purposes.

The principal object of this invention is to supplant the crude, annoying, and expensive battery hitherto considered the only practical source of therapeutic current by current derived from ordinary electric-light service-mains and to so govern the current as to insure absolute safety to the patient, and, further, to render the apparatus for utilizing this current operative on an alternating-current circuit of any of the commercial frequencies.

To these ends the said invention comprises the combination and arrangement of parts hereinafter more fully described, and particularly pointed out in the claims.

Referring to the accompanying drawings, Figure 1 is a front elevation of a switchboard with the apparatus and connections embodying this invention mounted thereon and connected thereto, and Fig. 2 is a bottom plan view of the foot-rheostat.

The apparatus constituting my invention is mounted upon a switchboard A of any suitable insulating material—such as slate, marble, or porcelain—and comprises, among other parts, an alternating-current motor a, direct coupled through a shaft b⁰ with a direct-current shunt-wound dynamo b, the two together constituting a rotary converter. The alternating-current mains are connected to bind-

ing-posts 1 and 2. The binding-post 1 is connected by wire 3 to a terminal 4 of the alternating-current circuit-breaker c, and thence through the carbon-breaks c' c² and coil c³ of cut-out, thence to terminal 5, no-arc fuse 6, thence by wire 7 to one of the lower points of the main switch d. The main binding-post 2 is connected by wire 8 to one of the terminals of the no-arc fuse 30, and thence by wire 10 to the other lower point of the main switch d. One of the upper points of this switch d connects by wire 11 to one of the terminals of a choking-coil rheostat or cycle-regulator e, the other terminal of which connects by wire 12 to one of the field-terminals of the motor a. The other field-terminal of this motor is connected by wire 13 to one of the lower middle points of a three-blade switch f and thence through the switch to wire 14, which connects to the motor-brush a'. The other motor-brush a² connects by wire 15 to one of the upper central points of the switch f and then through the central blade of said switch by wire 16 to the main switch d. The object of this cycle-regulator is to render the motor a adaptable to any of the commercial alternating-current systems. Many such systems require motors to be wound and constructed with especial reference to the periodicity of current that they employ. Hence a motor constructed to operate upon a one-hundred-and-forty-cycle system would not ordinarily work upon a twenty-five or fifty cycle system. My invention by the use of the cycle-regulator herein shown overcomes this difficulty.

The operation consists simply in adjusting the handle e' of the cycle-regulator e until the desired amount of impedance e² is in the motor-circuit to produce the required frequency.

The motor a is started by closing the switch d.

The direct-current dynamo b is preferably shunt-wound and provided with a field-rheostat g, the terminals of which are connected in the field-circuit of said dynamo by wires 17. The armature-brush b' of this generator connects by wire 18 to one of the binding-posts of a milliamperemeter, while the other binding-post of this meter is connected by wire 19 to one of the terminals j' of a shunt-rheostat i.

The circuit then passes out of the terminal j^2 of said rheostat and enters the left-hand blade of the reversing-switch z , passes through said switch into the wire 20, and passes into 5 the plus binding-post. The dynamo-brush b^3 is connected by wire 23 to the carbon-contact k' of the direct-current circuit-breaker k . The circuit then passes through the other carbon-contact k^2 , then by wires 24 25 to a 10 binding-post of the coil of the voltmeter l , thence out of the other binding-post of said voltmeter by wire 26, which connects to one of the binding-posts of the shunt-rheostat j . The circuit then passes by wire 26 to the 15 blade of the reversing-switch z , crossing over to the lower left-hand point of said switch, and by wire 27, terminating in binding-post 22. It will therefore be seen that the dynamo b , together with the shunt j and voltmeter l , is connected in shunt across the 20 binding-posts 21 22, while the milliammeter h will be in series with the object connected to said binding-posts. The shunt j , however, is provided with a stop j^3 at the lowest point 25 of resistance, (two hundred and twenty-five ohms,) so that never more than half of an ampere at one hundred and twenty-five volts ever passes said resistance. The reversing-switch z is connected, as shown, in such 30 manner that when in the "up" position current will flow in one direction through the object connected to binding-posts 21 and 22 and in the opposite direction when the said switch is "down." Therefore to furnish direct current to any object connect to the 35 binding-posts 21 and 22.

The voltmeter l is of peculiar construction, being adapted to coöperate with the circuit-breaker k and automatically break the direct-current-dynamo circuit when the voltage exceeds a predetermined amount. To this end I provide the voltmeter with an adjustable contact-point m , carried by an arm pivoted, as at m' , and provided with a knob m^2 , by 45 which the said contact-point may be adjusted to any desired position on the voltmeter-scale and is so mounted as to lie in the path of the index or pointer l^2 . The contact m is connected through its pivot and a binding-post 50 to a wire 28, which connects to one of the terminals of the coil of the circuit-breaker k , while the voltmeter-pointer is connected, as by wire 29, to the lower point of the no-arc fuse 30. When the voltage rises to such an 55 extent as to send the pointer l^2 into engagement with the contact m , current from the alternating-current-motor circuit will flow through the coils of the circuit-breaker k , causing it to break the circuit of the direct-current dynamo. The circuit of the alternating current will be from the lower point of fuse 29 to voltmeter-pointer, contact m , coil of circuit-breaker k , and thence by wire 60 32 to lower point of fuse 6.

65 The operation of the circuit-breaker k by the alternating current instead of the direct current is important, since the former is at

all times strong enough to actuate the circuit-breaker, whereas the direct current may at times be too feeble, though any increase there- 70 in might be fatal or injurious to the patient.

An alternating-current voltmeter to indicate the voltage of the service-mains may be connected to them at any suitable point.

I employ also a static alternating-current 75 transformer n , comprising a primary coil n' and three secondaries n^2 , n^3 , and n^4 , the secondary n^2 being the cautery coil and is provided with very coarse or heavy winding. The secondary n^4 produces the sinusoidal current and is much finer, as is also the coil n^3 . The circuit of the primary of said transformer is from the left-hand upper point of the main switch, through the said coil to a single-blade switch o , thence back to the upper right-hand point of said main switch. The secondary coils of this transformer are shown removed from the primary, but in practice are wound on cores and slipped over said primary. If a cautery current is desired, connect to binding-posts 33. If it is desired to use small lamps of half a volt or upward, connect to binding-post 34, and to obtain a sinusoidal current connect to binding-posts 35. These binding-posts are connected to their respective secondaries by the wires 36, 37, and 38, as clearly shown. A pulsatory current may be obtained by connecting to the binding-posts 40 41. These binding-posts connect by wires 42 43 with the primary of the induction-coil p of a pulsator having one terminal of its secondary connected, as by wire 44, with one of the brushes of the direct-current dynamo, while the other terminal connects by wire 45 through a single-blade switch q with a pendulum contact-maker p' , having an adjustable weight p^2 , by which the period of its oscillation may be varied. The oscillating contact-maker engages a fixed contact p^3 , which connects by wire 46 to the other brush b' of the direct-current dynamo. To obtain a faradic current, connect to binding-posts 47 48. These binding-posts are connected by wires 49 50 with the secondary of a faradic induction-coil r , one terminal of the primary 100 of which is connected to the brush b^3 of the dynamo and the other through the wire 51, single-blade switch s , vibrator r' , and contact r^2 with the other brush b' of the said dynamo. For charging storage batteries connect to binding-posts 52 53. These binding-posts are connected to the double-throw reversing-switch t by wires 54, the said switch being connected to wires 44 and 46, leading to and from the brushes of the dynamo. By 115 throwing this switch t up the current from the binding-posts 52 53 passes in one direction, while if the switch is thrown down the current from said binding-posts is reversed. As it is often useful in charging storage batteries 120 to reverse the current, this arrangement affords means for doing this without the necessity of disconnecting the batteries.

For the purpose of operating drills, saws

and the like I provide a flexible shaft v , having a handpiece v' at one end and at the other connected to a rotatable disk v^2 , which by means of an adjusting-nut v^3 may be brought into contact with and receded from a small power-pulley v^4 , mounted on the shaft connecting the motor and dynamo. The pulley v^4 is provided with a peripheral rubber band v^5 . I also provide for use with the flexible shaft attachment a three-speed reversible alternating-current foot-rheostat w , from which leads a cable w' , containing four wires, which connect, respectively, to the four binding-posts 55, 56, 57, and 58, the said binding-posts being connected, as shown, to the three-blade reversing-switch f , and thence to the motor a , as shown. This rheostat is operated by foot by means of the lever w^2 , which may be held by the locking device w^3 in any of the three 20 operating positions on either side of the central point.

Located above the meters are two pilot-lamps $x x$, which are connected in the alternating-current main circuit through the single-blade switch y .

Finally, the whole apparatus on the board A may be inclosed in a glass or other suitable casing to protect it against injury from the outside.

Having described a form of my invention, it is obvious that I may make changes and alterations therein without departing from the spirit of the same; but

What I claim, and desire to secure by Letters Patent of the United States, is—

1. In electrotherapeutic apparatus, the combination with a pair of alternating-current service-mains, of a rotary converter connected to said mains, and a combined voltmeter and automatic cut-out for limiting the voltage of the direct current from said converter.

2. The improved means for limiting the voltage of a source of electricity for therapeutic purposes, comprising a voltmeter measuring the voltage of the direct therapeutic current, an adjustable contact operated by said voltmeter, and a circuit-breaker operated through said contact.

3. In electrotherapeutic apparatus, the combination with a main alternating-current circuit, of a rotary converter operated by the current in said circuit, and means for automatically limiting the voltage of the direct current produced by said converter, said means comprising a voltmeter connected in said direct-current circuit, an adjustable contact

operated by said voltmeter, and a circuit-breaker located in said alternating-current circuit and operated by the contact of said voltmeter.

60

4. The combination with a pair of alternating-current service-mains, of a rotary converter connected thereto, a cycle-regulator connected in the alternating-current circuit of said converter, and electrotherapeutic apparatus connected in the direct and alternating current circuit of said converter.

5. The combination with a pair of alternating-current service-mains, of a rotary converter connected thereto, a cycle-regulator comprising an adjustable choking-coil connected in the alternating-current circuit of said converter, and electrotherapeutic apparatus connected in the direct and alternating current circuit of said converter.

75

6. In electrotherapeutic apparatus, the combination with a pair of alternating-current service-mains, of a rotary converter connected to said mains, and a pulsator operated by the direct current from said converter and adapted to produce pulsations of varying periods.

78

7. In electrotherapeutic apparatus, the combination with a pair of alternating-current service-mains, of a rotary converter connected to said mains, and a pulsator operated by the direct current from said converter and adapted to produce pulsations of varying periods, said pulsator comprising an induction-coil provided with a circuit-interrupter consisting of an oscillating contact-maker having an adjustable weight attached thereto.

85

8. In electrotherapeutic apparatus, the combination with a pair of alternating-current service-mains, of a rotary converter connected thereto, a flexible shaft and a coupling for connecting said shaft to said rotary converter.

95

9. In electrotherapeutic apparatus, the combination with a pair of alternating-current service-mains, of a rotary converter connected to said mains, and a rheostat connected in multiple with the direct-current terminals of said converter, substantially as and for the purposes herein specified.

100

In testimony whereof I affix my signature in presence of two witnesses.
